UNITED STATES PATENT OFFICE.

WILLIAM J. GROTHUIS, OF CHICAGO, ILLINOIS, ASSIGNOR OF ONE-HALF TO PHILIP A. SALISBURY, OF CHICAGO, ILLINOIS.

STAMPING DEVICE.

1,022,076.

Specification of Letters Patent.

Patented Apr. 2, 1912.

Application filed May 11, 1911. Serial No. 626,476.

To all whom it may concern:

Be it known that I, WILLIAM J. GROTHUIS, a citizen of the United States of America, and resident of Chicago, Cook county, Illinois, have invented a certain new and useful Improvement in Stamping Devices, of which the following is a specification.

My invention relates to rubber stamps of the kind in which one or more endless rubber bands are provided with raised letters or numerals for making the impression. These bands travel under a bridge which forms a backing for the rubber portions

15 which are required to make the impression at any particular time. When another impression is desired the bands are moved along until other portions thereof are brought into position below and against the 20 bridge. With the ordinary construction, however, there is always some tendency for the bands to creep on the bridge, and to thereby impair the accuracy of the impression.

25 The object of my invention is, therefore, to provide an improved arrangement for preventing creeping of the bands on the bridge, by the use of depressions in the backs of the bands, which depressions are of such 30 character that the back or inside of each band has a practically continuous flat wearing surface, and to thereby render the rubber stamp more reliable than heretofore, as will hereafter more fully appear.

35 In the accompanying drawings—Figure 1 is a side elevation of a rubber stamp embodying the principles of my invention. Fig. 2 is a vertical section of the same. Fig. 3 is a side elevation of the bridge of my 40 proved rubber stamp. Fig. 4 is a perspective of the said bridge, showing one end thereof in cross-section. Fig. 5 is a perspective of portions of the rubber bands which travel across the bridge, on the under 45 side thereof, and which carry the raised letters or numerals for making the impression.

As thus illustrated, my invention comprises a body A having a handle a at its upper end and a shaft a¹ extending horizontally from one side thereof to the other below said handle. On this shaft are the rolls a² which have the thumb-wheels a³ by which they are turned to properly adjust the stamp. At its lower end the frame or 55 body A has a horizontal member B called a

bridge. This bridge is of sheet metal, being trough-like in shape, and has its face formed with a longitudinal rib b extending centrally thereof. The rubber bands C are of the usual character, except that they are 60 thicker than usual and provided on their backs with transverse notches or grooves c which engage the rib b to hold the bands in proper position. These bands are, of course, elastic in character, and yield enough 65 to permit the thick portions between the notches c to ride over the rib b when it is desired to adjust the stamp for a different impression.

The letters or numerals, it will be understood, are raised on the outer surfaces of the bands, in the usual and well-known manner. The notches c are so positioned and spaced apart that each notch is directly back of a letter or numeral, or of a group 70 of letters or numerals, as shown, whereby the engagement of a notch c with the rib b insures accurate positioning of the bands. This also prevents creeping of the bands, as the strength and resiliency of the bands are 75 such that only forcible rotation of the wheels a³ can move the notches c out of engagement with the rib b. The notches c are, of course, adapted to contract while passing around the roll a², owing to the flexing of 80 the band at this point. Thus the accuracy of the device is insured, and a heretofore serious difficulty entirely remedied.

The advantage of the foregoing construction is that each band has its back or inside 85 formed with practically a continuous flat wearing surface which reduces wear and prevents the belts or bands from rapidly deteriorating in use. In other words, the depressions c are of minimum size, while 90 the portions between, which are subject to wear or abrasion, are flat and of maximum size or area. Thus, as stated, the inside of the belt is left practically flat, and in addition the maximum thickness of the belt is 95 of greater area; and in this way the belts will last longer. Moreover, the notches or depressions facilitate the flexing of the bands around the rolls.

It is the object of my invention to hold 100 the belt or band in place without using something that will readily wear away. This I do by putting the small projection on the bridge, which is of metal and thus not calculated to wear away, and by using the 105 110 115

rubber, which is soft and comparatively perishable, in such form that it has nothing to wear off. By a small projection I mean one which is relatively small, as also 5 the depressions in the band or belt.

What I claim as my invention is:

In a rubber stamp, a band having its face provided with means for making impressions, a stationary bridge across the flat face 10 of which the band travels to change the impression, and rotary means for operating the band, the said bridge having a small projection on the face thereof, and said band having a series of relatively small and sep- 15 arated positioning depressions on the back thereof, with substantial flat surfaces between said depressions, whereby the back of each band has a practically continuous flat wearing surface, said flat surfaces

adapted to engage the flat face of said 20 bridge, said projection adapted to engage said depressions, said band being thickened to accommodate said depressions in the form of transverse notches, said notches facilitating the flexing of the band around said 25 rotary means, and said projection being in the form of a rib extending longitudinally of the bridge at a point midway between the sides thereof, said notches adapted to contract while the band is passing around said 30 rotary means, as set forth.

Signed by me at Chicago, Illinois, this 5th day of May, 1911.

WILLIAM J. GROTHENHUIS.
